UNITED STATES PATENT OFFICE.

NICHOLAS A. COSENAS, OF NEW YORK, N. Y., ASSIGNOR TO THE W. F. POWERS COMPANY, OF NEW YORK, N. Y., A CORPORATION OF NEW YORK.

DISPLAY DEVICE.

Application filed November 18, 1925. Serial No. 69,777.

This invention relates to display devices, cards or the like and particularly to a device of this class constructed of printed, lithographed or otherwise characterized 5 cardboard, folded to form frame or background portions, and a part projecting from and setting within the frame and background portions whereby said part will be outstanding with respect to the remainder of 10 the device to produce a neat and attractive display; a further object being to provide a display device of the class specified which may be constructed from a single piece of cardboard, and in connection with which may 15 be mounted, if desired, an easel for supporting a predetermined part or parts of the display when in extended position; a further object being to provide a device of the class specified which may be compactly folded 20 together into a substantially rectangular package, facilitating the packing and shipment of the device or a number of such devices without danger of destruction to any part thereof; and with these and other objects in view, the invention consists in a display device of the class and for the purpose specified which is simple in construction, efficient in use, and which is constructed as 25 hereinafter described and claimed.

30 The invention is fully disclosed in the following specification, of which the accompanying drawing forms a part, in which the separate parts of my improvement are designated by suitable reference characters in 35 each of the views, and in which:

Fig. 1 is a front perspective view of one form of device which I employ in extended position.

Fig. 2 is a section on the line 2—2 of 40 Fig. 1.

Fig. 3 is a rear perspective view of the structure shown in Fig. 1.

Fig. 4 is a rear view of the blank from 45 which the device is formed with the parts in extended position.

Fig. 5 is a view showing the parts of the device shown in Figs. 1 to 4 inclusive in folded position.

Fig. 6 is a front view of a part of a modified form of device which I employ.

Fig. 7 is a face view of a blank from which the device shown in Fig. 6 is formed with the parts in extended position; and,

Fig. 8 is a plan view of the device shown 55 in Figs. 6 and 7 when in its folded position.

In Figs. 1 to 4 inclusive, I have shown one of my improved display devices comprising a central body part 10, side wall parts 11 foldable on the part 10 on the lines 12, and side flaps 13 foldable on the parts 11 on the 60 lines 14. In the structure shown in Figs. 1 to 5 inclusive, the parts 13 have projecting portions 13^a which are cut from the parts 11 and extend across the fold lines 14 and are designed to represent the corner portions 65 of boxes for display purposes, as seen in Fig. 1 of the drawing. It will be apparent that any projecting arrangement may be produced however to display articles of any kind or class as extensions from the parts 13 70 or extensions on the parts 11.

The general shape of the central part 10 is rectangular and is provided with an upwardly projecting regular portion 10^a foldable on the part 10 on the line 15, and which in the construction shown, resembles in outline, the head, neck, shoulder and body structure of a woman, it being understood that the parts 10 and 10^a will be printed and lithographed to produce a very attractive, 75 artistic arrangement for the display of predetermined merchandise, but the printing or lithographing is not indicated in that it forms no part of the invention. The remainder of the body of the girl or woman represented in the display is formed by a cut out portion 10^b on the part 10. In the representation, the girl or woman is pictured as sitting upon a fence, bench, stool or other support represented by the portion 10^c of the 80 part 10, which extends into the parts 11 or is partially formed by cut outs 11^a in said parts. The score or fold lines 12^a extend through the parts 10^c and 11^a as clearly seen in Fig. 4 of the drawing. The cut out 85 10^b of the part 10 terminates at the points 16, and horizontal score or fold lines 17 extend to the points 16 and also through the cut outs 11^a as clearly seen in Fig. 4 of the drawing.

A device fashioned in the manner thus far described may be folded from the extended position shown in Fig. 4 of the drawing to the display position represented in Figs. 1, 2 and 3 of the drawing by folding the parts 11—11 and 13—13 forwardly to form of the parts 11, side walls arranged at right angles to the part 10 and of the parts 13, angularly disposed frame members or flaps arranged at substantially 45 degrees to said side walls, 100 105 110

after which the part 10^a is folded forwardly on a score line 18 in parallel relation to the score line 17 and therebeneath, and the part 10^a is folded upwardly on the score line 17. 5 The projecting tongues 11^b on the parts 11 formed by the cut outs 11^a are passed over the upper edges of the cut outs 11^a to support the entire device in extended position as clearly noted in Figs. 1 and 3 of the drawing. 10 In this position of the parts, it will be apparent that the representation of the girl or woman is projected with reference to the back wall formed by the part 10 and sets within the side walls formed by the parts 11, 15 thus offsetting the figure with respect to the background. In this connection, it will also be apparent that the hole or aperture 19 formed by the cut out 10^b is concealed by said cut out 10^b when the display is set up, 20 especially when viewing the display directly from the front.

In folding the several parts of the display together to form the rectangular package seen in Fig. 5 of the drawing, the part 25 10^b is folded inwardly upon the part 10 on the line 15. It is preferred that an easel be employed for supporting the part 10^a in upright position so as to reinforce said part. In the construction shown, I have secured to 30 the part 10^a a strip of cardboard 20 having a foldable and apertured flap 21 adapted to engage and interlock with projecting tongues 22 on foldable sides 23 of another piece of cardboard secured to the part 10 or the 35 portion 10^c of said part. The operative position of the easel is shown in Fig. 3 of the drawing, and is also shown extended in Fig. 4. In the collapsed position of the device, it will be understood that the cut out 40 portions 11^a are foldable upon the part 10 in order that all of the parts of the device are contained within the general rectangular contour of the part 10, thus forming a neat and compact package for shipment.

45 In Figs. 6 to 8 inclusive, I have shown a slight modification wherein the use of the easel is eliminated, and the entire device is constructed from a single piece of cardboard. In this structure, I employ a part 50 24 similar to the part 10 and parts 25 and 26 substantially similar to the parts 11 and 13. At 24^a is shown a part extending from the part 24, and it is substantially the same as the part 10^a or is of contour representing that of the head and body of a girl or woman. The parts 24 and 24^a have extensions in the form of tongues 27 partially formed from the parts 25 which are adapted to enter apertures 28 formed in the parts 55 25 when the display is in set up position as seen in Fig. 6 of the drawing. Two fold lines 29 and 30 are employed on the part 24 to extend the part 24^a forwardly and upwardly as in Figs. 1 to 3 inclusive, and a 60 portion 24^b of the part 24 is cut out in the

manner of the cut out 10^b to represent the legs of the girl or woman. With the structure shown in Figs. 6 to 8 inclusive, it will be apparent that the parts 24^a when locked in engagement with the parts 25 is supported in upright position without the use of an easel. In compactly folding the parts together, a score or fold line 31 is provided at the top of the part 24 proper; this line extends centrally through the projecting 75 tongues 27. The result of the collapsing of the entire display is represented in Fig. 8 of the drawing, wherein it will be noted that the only parts which project are the tongues 27, thus forming a substantially rectangular and compact package of the display device.

It will be understood that I am not necessarily limited to either specific form of construction herein shown and described, nor 80 am I limited to any particular subject matter of the display nor the arrangement of display bodies on the several parts of the device; and various changes in, and modifications of, the construction herein shown 85 and described may be made within the scope of the appended claims without departing from the spirit of my invention or sacrificing its advantages.

Having fully described my invention, what I claim as new and desire to secure by Letters Patent, is:—

1. A display device of the class described comprising a central part, side parts integral with and foldable forwardly and angularly with respect to the sides of the central part, the central part having an upwardly extending part of predetermined contour, said part being foldable forwardly to offset the same with respect to the central part and including a portion cut from the central part and of a contour supplementing the contour of said upper part and offset with relation to the central part.

2. A display device of the class described comprising a central part, side parts integral with and foldable forwardly and angularly with respect to the sides of the central part, the central part having an upwardly extending part of predetermined contour, said part being foldable forwardly to offset the same with respect to the central part and including a portion cut from the central part and of a contour supplementing the contour of said upper part and offset with relation to the central part, and means cooperating with the side parts for retaining the upper part in its offset and upright position.

3. A display device of the class described comprising a central part, side parts integral with and foldable forwardly and angularly with respect to the sides of the central part, the central part having an upwardly extending part of predetermined contour,

said part being foldable forwardly to offset the same with respect to the central part and including a portion cut from the central part and of a contour supplementing the 5 contour of said upper part and offset with relation to the central part, means cooperating with the side parts for retaining the upper part in its offset and upright position, and all of said parts being foldable 10 into a compact package substantially rectangular in form and having substantially straight, parallel lines.

4. A display device of the class described comprising a central part constituting the 15 background of the display, side parts foldable forwardly and laterally with respect to the sides of the central part and constituting display wings margining and offsetting the central part or background, a characterized 20 display part fashioned from the upper end of the central part and including a portion cut from said central part, said portion having a contour cooperating with the contour of the display part to produce a predetermined display, said display part being foldable forwardly with respect to the central part to offset said display part with respect to the central part, and means holding said display part in operative position.

5. A display device of the class described comprising a central part constituting the background of the display, side parts foldable forwardly and laterally with respect to 35 the sides of the central part and constituting display wings margining and offsetting the central part or background, a characterized display part fashioned from the upper end of the central part and including 40 a portion cut from said central part, said portion having a contour cooperating with the contour of the display part to produce a predetermined display, said display part being foldable forwardly with respect to the central part to offset said display part with respect to the central part, means holding said display part in operative position, and cooperating means on said side parts and said display parts for maintaining the entire device in operative position.

6. A display device of the class described

comprising a central part constituting the background of the display, side parts foldable forwardly and laterally with respect to the sides of the central part and constituting 55 display wings margining and offsetting the central part or background, a characterized display part fashioned from the upper end of the central part and including a portion cut from said central part, said portion having a contour cooperating with the contour of the display part to produce a predetermined display, said display part being foldable forwardly with respect to the central part to offset said display part with respect to the central part, means holding said display part in operative position, cooperating means on said side parts and said display parts for maintaining the entire device in operative position, said display part including a foldable portion, and means for maintaining the foldable portion in upright position.

7. A display device of the class described comprising a central part constituting the background of the display, side parts foldable forwardly and laterally with respect to the sides of the central part and constituting display wings margining and offsetting the central part or background, a characterized 70 display part fashioned from the upper end of the central part and including a portion cut from said central part, said portion having a contour cooperating with the contour of the display part to produce a predetermined display, said display part being foldable forwardly with respect to the central part to offset said display part with respect to the central part, means holding said display part in operative position, cooperating 75 means on said side parts and said display parts for maintaining the entire device in operative position, all of said parts being fashioned from a single piece of cardboard, and said parts being foldable into a compact package substantially rectangular in 80 form.

In testimony that I claim the foregoing as my invention I have signed my name this 2nd day of Nov., 1925.

NICHOLAS A. COSSENAS.
